UNITED STATES PATENT OFFICE.

ROBERT B. WILSON, OF CINCINNATI, OHIO.

BRICK-MACHINE.

SPECIFICATION forming part of Letters Patent No. 267,814, dated November 21, 1882.

Application filed August 19, 1882. (No model.)

To all whom it may concern:

Be it known that I, ROBERT B. WILSON, a citizen of the United States of America, residing at Cincinnati, in the county of Hamilton and State of Ohio, have invented an Improvement in Brick-Machines, of which the following is a specification, to wit:

My invention relates to machines for forming and pressing brick; and it consists in the combination, with a bed or main frame, of a sliding carriage or frame constructed to operate the pressing devices, and in such other novel points as will be hereinafter more fully described, and specifically pointed out in the claims.

In order to enable others skilled in the art to which my invention appertains to avail themselves of the benefits of the same, I will now proceed to describe its construction and operation, referring to the accompanying drawings, in which—

Figure 1 is a perspective view of my machine, showing the sliding carriage at the rear end of its stroke; Fig. 2, a plan view of the same at the forward end of the stroke; Fig. 3, a central longitudinal section through the machine in the position shown in Fig. 2; Fig. 4, a plan view of the bed with its sliding frame, all mechanism above said frame being removed. Fig. 5 is an enlarged plan view of one of the rear corners of the machine, showing the friction-rollers in bed-frame, and position and action of the delivery-slide. Fig. 6 is a cross-section of the machine just in rear of the forward pressing mechanism, and Fig. 7 is a detail view of part of the delivery-slide.

Similar letters of reference denote similar parts throughout the several views.

A represents the bed of my machine, and B a frame or carriage sliding horizontally in ways C C, secured to the bed. These ways or guides C C are supplied with anti-friction rollers c c at the points where pressure is given to the clay during the formation of bricks, in order that the carriage may move with the greatest ease. The bed or main frame A is provided at suitable intervals with cross-bars A', running across the machine, and upon the centers of these cross-bars are set the boxes or pressing-chambers D D, into which the clay is fed from a hopper. (Shown by dotted lines in Fig. 1.)

The plungers E E' rest upon the cross-bars A', which form the bottom of the pressing-chambers D D, and each of these plungers or followers is bifurcated at its rear end, and is provided with a friction-roller, e, as shown. One of the plungers (marked E') in each pair is longer than the other for a purpose which will be presently seen. Over each of the plungers E E' is a cap, F, which is bolted to the box D and the bed A, and is connected to the cross-bar A' by metal straps f f to act as guides, preventing the plungers from getting out of place during the operation of the machine. The plunger E' has always its forward end within the box D, and needs no other guide than the straps f f; but the shorter plunger E, being drawn completely out of the box to facilitate the discharge of the pressed bricks, has its rear end provided with projections above and below, which overlap the edges of the caps F and cross-bar A', as seen at e', and thus serve to keep this plunger always in line. The caps F are slotted transversely from the bed A to the box D, as seen at f', and the pivot of the friction-wheel e is extended upward through this slot, and its upper end provided with another roller e' above the cap.

The forward and rear sides of the boxes D are provided near their upper edges with slots d d, in which works a cut-off slide, D', having one end solid, as shown, and the other provided with an opening, d', of a size corresponding with the interior of the pressing-chamber, and on the end next the end bar of the sliding frame these slides D' D' are provided with a beveled catch or projection, d'. The end bars of the sliding sash or frame are each provided with a latch, B', having beveled hooks b upon their inner sides to engage with the projection d' on the cut-off slides. These latches B' B' are secured to the short standards b' b', having headed lower ends, and free to slide vertically through the sash or frame B. The bed A is provided with two rods, a a, which extend across the machine from side to side of the bed at the proper points, and as the sash B slides back and forward in its ways the headed lower ends of the standards b' are struck and raised by these rods a, carrying with them the latches B' for engagement and disengagement with the cut-off slide D'. The movement of these latches

is limited by a set-screw, b^2 , passing through the latch and bearing on the frame B. The plungers E E' are thrown forward at the proper time, in the movement of the sliding sash, by a series of cams upon the tracks L M on the inner sides of said sash, upon which the friction-rollers e run, and are retracted again by two cam-bars, G G', secured to the frame above the caps F, and bearing against 10 the friction-rollers e^2 , as shown.

H is a sliding bar running longitudinally through the machine upon one side of the boxes D D, flush with the upper surface of the cross-bar A', and this bar is connected at each 15 end to a slotted lever, I, pivoted to a projection, I', on the bed of the machine, near the opposite side of the same, and extending a short distance beyond said pivotal point. Upon each end of the sliding sash is a small dog, h, 20 arranged to strike the short arm of the levers I at the proper time to give the slide H a reciprocating motion for the purpose of carrying off the brick after it has been pressed and fed onto the slide. As the movement of this 25 slide is rapid the brick might slide upon its smooth surface, and to prevent this I provide the slide, in the rear of the points at which the brick is fed upon it, with a dog, h', pivoted in a slot in the slide, and held above its upper 30 surface by a spring, h², as seen in Fig. 7.

In operation, when the sash or frame B is at the extreme rear end of its stroke, as seen in Fig. 1 of the drawings, the rear pressing-chamber is closed, the brick having been 35 formed, fed out onto the slide H, and carried off. The plungers E E' are drawn back as far as possible, and the other thrown forward until it is entirely within the pressing-box. The forward pressure-chamber is open, the cut-off 40 slide being engaged with the catch on the sash, and shoved back until the opening d' is over the box D, allowing the clay to be fed down. The plungers E E' are drawn back and their friction-rollers rest against the tracks i k upon 45 opposite sides of the sliding frame. These tracks are straight for a short distance, so that when the sash starts forward the plungers will not be forced up until the slide has been closed over the top of the pressing-chamber. 50 When the chamber has been closed and the feed of the clay cut off the standards b' b' strike and are raised by the rod a, thus disengaging the catch B' from the slide. In the meantime the plunger E' of the rear pair is being forced back by the contact of the cam-bar G with the roller e^2 , and the plunger E forced forward into the box by the cam o' on the track M. As the frame moves forward the plungers in the forward pair are forced together by the 55 cams l m until the brick has been sufficiently pressed. The other plungers have now been forced back by the bars G G' until the rear press-box is entirely free. At this point the catch B' at the rear end of the sash is raised 60 and engaged with the slide D', and as this slide is moved back by the motion of the frame

to open the press-box to receive the clay the short plunger E of the forward pair is suddenly retracted by the cam-bar G' until it has entirely left the box, the track M being cut 70 away at o to allow of this retraction. At the same time the plunger E' is forced forward by the cam n, carrying the pressed brick with it, until it rests on the slide H outside of the press-box. At this moment the dog h upon 75 the rear end of the frame strikes the lever I and moves the slide out, where the brick can easily be reached and removed by a workman. It will be seen that during this movement of the slide the plungers are riding over the sections of the track marked p q, which are straight or parallel with the motion of the sash, in order that the plungers shall not interfere with the carrying off of the brick. The sash has now reached the forward limit of its stroke and 80 is reversed, reversing also the motion of the parts.

It will be seen that the amount of retraction given the plungers, and in consequence the amount of clay the press-box will hold, is regulated by a short plate, g', placed on top of the bars G G', near their ends, and secured by set-screws passing through slots g g, in order to render the plates adjustable. 85

The power is applied by means of a pitman, 95 P, secured to one end of the sliding frame and connected to an engine or other suitable motive power. The slide H works under the plungers E E', and the dog h', being hinged in the slide, passes readily under the plunger, 100 and is thrown up again by the spring beneath it.

It is obvious that the construction of this machine may be changed somewhat without departing from the spirit of my invention—as, 105 for instance, the sliding carriage may be made stationary, and the pressure-boxes and their plungers be constructed to slide back and forth to produce the same result. It will be seen that all the bearing parts of the machine are 110 provided with anti-friction rollers to reduce the friction and bring the power required to run the machine to the lowest possible point. The machine may also be made vertical without material change, and in this case may also be 115 cut in two and worked with the sash in two parts having the same or an alternating motion. 120

It will be found advantageous to provide the pressing-chambers with air-vents, as shown in 125 the drawings, and they should be very small at their inner ends and larger at their outer ends, so that no material may be pressed out through them, or, if this does occur, it may pass out freely and prevent clogging the vents. 130

It is obvious that the capacity may be increased at a very small expense by extending the sash to operate one or more additional pressing devices, or by attaching another sash or carriage alongside the first to be actuated 135 from the same pitman; and it may also be used to press half-dried brick, as is now usually done.

with a hand-press, much better and more rapidly by simply feeding the formed brick into the chambers, to be operated upon in the same manner already described for the raw material.

5. The machine constructed as described is what is usually known as a "dry-brick machine," being adapted to form the bricks from the material as taken from the ground without moistening or similar preparation.

10. Having thus fully described my invention, what I claim as new, and desire to secure by Letters Patent, is—

1. In a brick-machine, the combination of a pressure-chamber, a sliding cut-off, a pair of 15 plungers of unequal length, and suitable operating mechanism, substantially as described.

2. In a brick-machine, the combination, with two or more pressure chambers or boxes provided with sliding cut-offs, and having opposite plungers of unequal length, of a carriage or frame provided with means for operating the sliding cut-offs, and with cams and retracting cam-bars adapted to advance and retract the plungers, substantially as described.

25. 3. In a brick-machine, the combination, with pressure-chambers having plungers and sliding cut-offs, of a reciprocating carriage adapted to operate said plungers and cut-offs, substantially as described.

30. 4. In a brick-machine, the combination, with a pair of pressure-chambers, each provided with plungers and cut-offs, of a reciprocating carriage adapted to actuate said plungers and cut-offs in such a manner that during a single 35 movement of the carriage in either direction the material in one chamber will be pressed and discharged while the other chamber is being filled, substantially as described.

40. 5. In a brick-machine, the combination, with a pair of pressure-chambers, each provided with a pair of reciprocating plungers and a sliding cut-off, of a sliding carriage provided with devices adapted to actuate the cut-offs and alternately cover and uncover the pressure-chambers, and having means for advancing and retracting the plungers, whereby in alternate chambers both plungers are advanced to press the brick, and one retracted while the other is advanced to discharge the brick, substantially as described.

45. 6. In a brick-machine, the combination of a bed or frame having guides or ways provided with friction-rollers, pressure-chambers supported on said frame and having sliding cut-offs, reciprocating plungers provided with friction-rollers, and a sliding carriage adapted to operate said plungers and cut-offs, substantially as described.

50. 7. In a brick-machine, the combination of 60 pressure-chambers having reciprocating plungers and cut-offs, a reciprocating delivery-slide, and a reciprocating carriage adapted to operate said cut-offs, plungers, and slide, whereby the bricks are pressed and delivered, substantially as described.

65. 8. In a brick-machine, the combination of

pressure-chambers arranged in pairs, slotted movable cut-offs adapted to alternately cover and uncover said chambers, plungers of unequal length adapted to press the material in 70 said chambers, a reciprocating delivery-slide, and a carriage having means for actuating said cut-offs, plungers, and slide, whereby one chamber in each pair may be filled with material while a brick is pressed in and delivered 75 from the other chamber, substantially as described.

9. In a brick-machine, two stationary pressing-chambers, each provided with a pair of reciprocating plungers, in combination with a 80 horizontally-sliding carriage adapted first to advance the plungers to press the brick and then retract one plunger in each pair while the other is advanced to discharge the brick, and finally to return the plungers to their normal 85 position, substantially as described and shown.

10. The combination, in a brick-machine, of a stationary pressing-chamber, provided with a sliding cut-off, with a horizontally-reciprocating carriage adapted to be engaged with 90 and disengaged from the cut-off at stated points in its movement, substantially as and for the purpose set forth.

11. In a brick-machine, a reciprocating delivery-slide, in combination with a reciprocating carriage adapted to engage with and operate the slide to deliver the brick, substantially 95 as described and shown.

12. The combination, in a brick-machine, of a reciprocating delivery-slide, an operating lever or arm, and a horizontally-reciprocating carriage provided with a dog for engagement with the said operating-lever, substantially as and for the purpose described.

13. In a brick-machine, a reciprocating delivery-slide provided with spring-actuated dogs, substantially as and for the purpose described.

14. The latch B', having hooked ends b b and standards b' b', adapted to slide vertically through the sliding carriage B, in combination 110 with means for raising the latch, substantially as described and shown.

15. The combination, in a brick-machine, of the reciprocating plungers E E', provided with friction-rollers e e², with a horizontally-reciprocating carriage having cam-tracks L M, and retracting devices or bars G G', shaped to correspond with their respective tracks, substantially as and for the purpose set forth.

16. In a brick-machine, the adjustable auxiliary plates g', by means of which the size of the 120 pressing-chambers may be regulated to receive a larger or smaller quantity of material, substantially as shown and described.

17. The retracting bars G G', provided with 125 the adjustable auxiliary plates g' g' near their ends, substantially as described and shown.

18. In a brick-machine, the plungers E E', moving between guides, in combination with the cross-bar A' and caps F, substantially as 130 described and shown.

19. The combination, in a brick-machine, of

the plungers E E', having guides e', with the cross-bar A', and slotted caps F, connected by metal straps f f, substantially as and for the purpose set forth.

5 20. In a brick-machine, the sliding cut-off D', provided with opening d' for the passage of material, in combination with the pressing-chamber D, substantially as shown and described.

In testimony whereof I affix my signature in presence of two witnesses.

ROBERT B. WILSON.
